AU 292 EX

OR D 14.261

D/4.261.

UNITED STATES PATENT OFFICE.

FRANCES A. RANSOM, OF PALATKA, FLORIDA.

DESIGN FOR A FEATHER FAN OR SCREEN.

SPECIFICATION forming part of Design No. 14,261, dated September 4, 1883.

Application filed May 15, 1883. Term of patent 3½ years.

To all whom it may concern:

Be it known that I, FRANCES A. RANSOM, of the city of Palatka, in the county of Putnam and State of Florida, have designed and originated a Shape or Form for Feather Fans and Screens, of which the following is a full, clear, and exact description, reference being had to the accompanying photographic illustration, making part of the specification.

10 The nature of my design is fully illustrated in the accompanying photograph, to which reference is made.

A represents the handle of the fan or screen.

15 B represents the foundation, of pasteboard or other material, to which the handle and feathers are attached.

C represents the feathers completing the form or shape of the fan or screen and attached to the foundation.

20 D E represent the points of contact of the handle and foundation.

F represents the connection of the points of the crescent shape.

I am aware that fans and screens composed of feathers and ornamented by flowers and leaves formed of feathers and with handles attached to the bottom or side of the fan are not new, and I do not claim them.

25 The distinctive character of my design is found in the open space in the body of the fan or screen, by means of which a crescent or horseshoe form is secured.

30 What I claim as my invention and design is—

A design for feather fans and screens, ornamented as shown, having an open space in the lower portion of the body thereof, whereby a crescent or horseshoe shape is secured to the fan or screen, as shown and described.

FRANCES A. RANSOM.
